UNITED STATES PATENT OFFICE

HOWARD W. HARRINGTON, OF BARTLESVILLE, OKLAHOMA

DESIGN FOR AN ADVERTISING SIGN

Application filed July 14, 1930. Serial No. 36,345. Term of patent 14 years.

To all whom it may concern:

Be it known that I, HOWARD W. HARRINGTON, a citizen of the United States, residing at Bartlesville, in the county of Washington and State of Oklahoma, have invented a new, original, and ornamental Design for Advertising Signs, of which the following is a specification, reference being had to the accompanying drawing, forming part thereof.

I claim:

The ornamental design for an advertising sign, as shown.

HOWARD W. HARRINGTON
